UNITED STATES PATENT OFFICE.

FREDERIC S. MILLER, OF NEW YORK, N. Y.

ASPHALT-MELTER.

SPECIFICATION forming part of Letters Patent No. 623,613, dated April 25, 1899.

Application filed June 20, 1898. Serial No. 683,961. (No model.)

To all whom it may concern:

Be it known that I, FREDERIC S. MILLER, a citizen of the United States of America, and a resident of New York, borough of Brooklyn, county of Kings, State of New York, have invented certain new and useful Improvements in Asphaltum-Melters, of which the following is a specification.

My invention relates to the economical and continuous melting of asphaltum or similar pitchy substances, and is designed to secure the same by the direct application of the heat in a furnace without subjecting the asphaltum to the danger of spoiling by overheating, as is commonly the case in the use of the ordinary apparatus.

Asphaltum melts at or about the temperature of 325° Fahrenheit; but the subjecting of the same to any considerable excess temperature immediately and completely spoils the asphaltum and renders it valueless for the uses to which it is ordinarily applied.

Asphaltum is usually supplied to the trade in lumps and large masses, which have to be broken up and melted in order to use the asphaltum in a liquid state. To accomplish this without injuring the asphaltum and continuously and economically without the use of steam-heater or other costly apparatus, I have designed the herein-described apparatus, which is illustrated in the accompanying sheet of drawings, in which—

Figure 1 is a vertical central section of my apparatus, and Fig. 2 is a detail drawing showing the internal wire screen.

Throughout the drawings like reference-figures refer to like parts.

1 represents an ordinary iron kettle, which is mounted in the fire-box shell 2, in which is the ordinary form of grate 3, with fire-brick lining 4 for the fire-box proper.

5 represents the supports for the apparatus, and 6 is a smoke-stack.

In the lower portion of the kettle 1 I place a netting 7, which has suitable projections 8 formed thereon or connected thereto for holding the netting at a distance of an inch or so from the bottom and lower sides of the kettle.

This netting may be made of large mesh—two 50 inches or thereabout. It does not extend to

the top of the kettle, but leaves a considerable portion of the upper interior of said kettle uncovered.

9 is a discharge-pipe connected to the lowest point in the kettle and carrying the melted asphaltum to any suitable receptacle. (Not shown.) Inasmuch as the discharge-pipe passes through the fire-box or furnace it is advisable to protect that portion of it in said furnace by a suitable envelop 10 of asbestos 60 fireproof cement or other non-heat-conducting material.

The operation of my invention is as follows: A fire is built in the furnace of coal or other suitable fuel and maintained to produce 65 sufficient heat to melt the asphaltum in the lower portion of the kettle. The asphaltum is charged into the kettle in sufficient quantity to fill the same to the top. The netting 7 prevents the large lumps of asphaltum from 70 falling down into contact with the kettle, which frequently attains a temperature sufficient to burn them. It also prevents such lumps and any impurities from collecting in the mouth of the discharge-pipe and checking 75 the flow of melted asphaltum, and thus retaining it until it reaches a destructive temperature. At the same time the upper portion of the charge packs down solidly against the upper portion of the sides of the kettle 80 and forms a roof, which retains the hot air in the kettle, thus facilitating the melting.

The asphaltum as melted from the surface of the lumps drips down to the bottom of the kettle and rapidly runs out through the discharge-pipe before it has a chance to be subjected to a destructive temperature. The sheathing on the discharge-pipe prevents the same from becoming heated to a dangerous degree.

The advantages of my invention consist in its economy, enabling asphaltum to be melted in comparatively small quantities by the direct action of fire on the bottom of the kettle, and in the continuous nature of the operation, the cool asphaltum being continuously piled up on top of the kettle, where it is in a temperature sufficiently low so that the workmen can get on top of it and break up the lumps by pounding, and, lastly and mainly, 95 100

in the fact that the asphaltum cannot be overheated, as it runs out of the apparatus within a very short time after it is raised to a melting temperature and cannot become clogged or dammed up in the kettle.

Various changes could be made in the details of construction of my apparatus without departing from the spirit and scope of the invention so long as the relative arrangement of parts illustrated in the drawings and mode of operation described in the specification are preserved.

Having therefore described my invention, what I claim as new, and desire to protect by Letters Patent, is—

1. In an apparatus for melting asphaltum, the combination of a kettle, the furnace thereunder, the discharge-pipe connected to the lowest point of the kettle, and the netting arranged in the lower portion of said kettle, substantially as described.

2. In an apparatus for melting asphaltum, the combination of a kettle, the furnace thereunder, the discharge-pipe connected to the lowest point of the kettle, and the netting arranged in the lower portion of said kettle, together with the sheathing of non-conduct-

ing material around that portion of the discharge-pipe inside of the furnace.

3. In an apparatus for melting asphaltum, the combination of a kettle, the furnace thereunder, the discharge-pipe connected to the lowest point of said kettle, and the netting arranged in the lower portion of said kettle, the said netting extending only a portion of the way up the sides of the kettle, substantially as described.

4. In an apparatus for melting asphaltum, the combination of a kettle, the furnace thereunder, the discharge-pipe connected to the lowest point of said kettle, and the netting arranged in the lower portion of said kettle and extending only a portion of the way up the sides thereof, together with the sheathing of non-heat-conducting material around that portion of the discharge-pipe inside of the furnace, substantially as described.

Signed by me, at New York city, this 16th day of June, 1898.

FREDERIC S. MILLER.
